UNITED STATES PATENT OFFICE

2,153,307

TITLE MAKING MACHINE

Henry Jansen, Chicago, Ill., assignor to Janline
Tile Company, Inc., Chicago, Ill., a corporation
of Illinois

Application April 1, 1937, Serial No. 134,315

8 Claims. (Cl. 25—20)

The invention relates to tile making machines and more particularly to an improvement in machines for making hollow building tile having exterior longitudinally extending recesses provided as receptacles for nails or other devices for securing fixtures, molding and similar materials to the tile when positioned in the walls or ceilings of a room.

The invention comprises an attachment for tile making machines whereby the completed tile is provided with a plurality of longitudinally aligned recesses extending through the side walls thereof and terminating in a partition wall, the advantages of such construction and arrangement of recesses being more fully explained and described in my co-pending application, Serial No. 134,314, filed April 1, 1937.

It is an object of the invention to provide an improved attachment for tile making machines of the kind described whereby the tile blocks are recessed as described while the material is still plastic, the forming of the recesses being a part of the operation of manufacturing.

Another object of the invention is the provision of improved means operable to provide recesses of substantial depth in the side walls of tile blocks without weakening the tile for handling while plastic or lessening its load resistance when the material has hardened.

Many other objects and advantages of the construction and method of assembly herein shown and described will be obvious to those skilled in the art from the disclosure herein given.

To this end my invention consists in the novel construction, arrangement and combination of parts herein shown and described and more particularly pointed out in the claims.

One embodiment of the present invention is shown for illustrative purposes in the drawings, in which:

Fig. 1 is an elevational view of the discharge end of a tile making machine having the device of the invention mounted thereon;

Fig. 2 is a view along the line 2—2 of Fig. 1;

Fig. 3 is a side elevational view of a fragmentary portion of the machine showing the groove forming devices movable into and out of operative relation to a continuous tile block while it is forced along a runway and is severed into sections of standard length; and

Fig. 4 is an enlarged scale view taken along the line 4—4 of Fig. 1 illustrating the details of a typical recess formed by the device.

Referring now more particularly to the drawings, the numeral 10 generally designates a tile

forming machine, only the discharge end of which is shown in the drawings. The machine provides a hopper 11, an expressing auger 12 which forces the plastic material into a casing 13 under pressure, and a die 14 contained in a frame 19 through which the material is discharged in the form of a continuous hollow tile block 15 resting upon and propelled along a platform 16. The block 15 is shown as having two partition walls 17 with longitudinally aligned recesses 18 formed in opposite sides of the block, there being a line of recesses for one or both sides of the tile. The invention is adapted for use with tile blocks having only one partition wall 17 and also for use with blocks having a plurality of such walls.

The recesses 18 are formed in the side walls of the block 16 while the block is passing through the frame 19. The device or attachment for forming the recesses 18 includes a plate or block 25 fastened to the machine 10 by a plurality of bolts 26. The plate 25 provides a support for cam actuated mechanism operable to move a pair of arms 27 into and out of operative engagement with the opposite sides of the block 15 as it is forced through the frame 19 by the action of the auger 12.

The cam actuated mechanism includes a shaft 28 rotated by a chain drive 29 operatively connected with a source of power by any suitable means not shown. A cam member 30 mounted on and rotatable by the shaft 29 has oppositely projecting arms 31 positioned to successively engage rollers 32 respectively mounted on the adjacent ends of two reciprocally movable bars 33. A plate 34 connects each arm 27 with a corresponding one of the bars 33 in such a manner that longitudinal movement of the bars 33 by engagement therewith of the projecting cam arms 31 causes a corresponding longitudinal movement of the arms 27.

A plurality of U-shaped plates 35 mounted on the block 25 provides supports and serves as guides for the bars 33 preventing other than longitudinal movement thereof. Outward movement of each bar 33 is resisted by a helical spring 36 having one end projecting into a recess 37 provided for that purpose in the end of the bar and having its other end in bearing contact with an abutment block 38.

Fig. 1 shows the arms 27 and the bars 33 in their respective positions of maximum outward movement wherein the free ends of the arms are out of contact with the tile block 15. As the shaft 28 is rotated from the position shown, the

rollers 32 ride over the longitudinal edges of the cam arms 31, thereby permitting the springs 36 to move the bars 33 inwardly and also to move the arms 27 inwardly through apertures 39 from the opposite sides of the frame 19 and then into the plastic material comprising the block 15. The free end of each arm 27 comprises a thin wedge and the adjacent portion which follows the wedge portion into the plastic material is transversely corrugated or similarly distorted. The plates 34 are of such a length and so positioned that the arms 27 lie in the median plane of the partition wall 17 of the block 15 and the effective length of the arms 27 is such that the depth of the recesses 18 formed thereby in the block 15 is equal to or greater than the length of a nail or other article adapted to be driven or wedged therein. The recesses 18 thereby extend inwardly as shown beyond the side walls of the block 15 and into the partition wall 17 a substantial amount and are spaced substantially from the boundaries of the partition wall.

The arms 27 are fastened on the plates 33 respectively by screw bolts 40 thereby permitting adjustment of the effective length of the arms to adapt the device for recessing blocks of different thicknesses or for providing recesses 18 of different depths in the block.

The length and spacing of the recesses 18 obviously depends upon the rate of rotation of the shaft 28 relative to the rate of advancement of the block 15 through the frame 19.

The cam construction is such that the arms 27 are moved rapidly to their position of maximum embedment in the block 15, this occurring while the rollers 32 are travelling over the adjacent sides of the cam arms 31 and into contact with the hub portion of the cam member 30. The embedment of the arms 27 remains constant while the rollers 32 are in contact with the hub portion of the cam member 30 and since this contact is for a relatively longer period, the recesses 18 have a substantial length of uniform depth corresponding to this period of contact. The rollers 32 are then again engaged with the edges of the cam arms 31 resulting in the rapid withdrawal of the arm 37 and the completion of a recess 18. During the relatively short period in which the rollers 32 contact with the ends of the cam arms 31, as shown in Fig. 1, the arms 27 clear the block 15 and this period determines the amount of spacing between the successively formed aligned recesses.

The recesses 18 formed as described have their extreme outer end portions convergent inwardly and of a width determined by the overall thickness of the distorted portion of the arms 27. The intermediate portion of the recesses, formed while the arms 27 are stationary, have sinuous or corrugated or similar shaped bounding side faces spaced apart in an amount equivalent to the normal thickness of the arms 27. The lateral dimensions of the recesses 18 are preferably equal to or slightly less than the diameter of a nail adapted to be driven therein.

Description and disclosure of the major portion of the machine 10, including the power drive therefor, is omitted as being unnecessary to an understanding of the invention which comprises the devices for forming the recesses 18 while the block 15 is being advanced in a manner well known in the art. The shaft 28 is preferably connected with the mechanism driving the auger 12 and will thus be operated at a speed corresponding to the rate the auger advances the plastic tile material.

The shaft may also be actuated by a separate power drive operating at a rate corresponding to the rate of operation of the auger 12 and thereby provide recesses 18 of uniform length and of uniform longitudinally aligned spacing. 5

Thus it will be seen that I have provided an attachment mounted on and operated in connection with a tile machine providing longitudinally aligned recesses of the kind described in the side walls of a tile block in the process of formation, 10 the recesses being of substantial depth and so positioned and spaced that the blocks so recessed are not weakened for handling while plastic and their load resistance after hardening is unimpaired. 15

Having thus described my invention it is obvious that various immaterial modifications may be made in the same without departing from the spirit and scope of my invention, hence I do not wish to be understood as limiting myself to the exact form, construction, arrangement and combination of parts herein shown and described or uses mentioned.

What I claim as new and desire to secure by Letters Patent is:

1. A device for forming a plurality of longitudinally aligned recesses in a moving block of plastic material, said device comprising an elongated bar or plate reciprocally movable into and out of the path of said block and having its opposite edges so positioned as to be intersected throughout their length by a plane parallel to said path, and mechanism operable to reciprocally move the bar into and out of engagement with the block. 35

2. A device for forming a plurality of longitudinally aligned recesses in a moving block of plastic material, said device comprising a relatively thin elongated bar movable into and out of the path of said block and having its opposite edges so positioned as to be intersected throughout their length by a plane parallel to said path, and mechanism operable to reciprocally move the bar into and out of engagement with the block and to maintain the bar stationary for an interval following each movement of the bar. 45

3. A device for forming a plurality of longitudinally aligned recesses in a moving block of plastic material, said device comprising a relatively thin elongated bar or plate movable into and out of the path of said block and so positioned that its opposite edges are intersected throughout their length by a plane parallel to said path, said bar providing a corrugation extending substantially in the direction of movement of the block, and mechanism operable to reciprocally move the bar into and out of engagement with the block and to maintain the bar stationary for an interval following each movement of the bar. 55

4. A device for forming a plurality of longitudinally aligned recesses in a moving block of plastic material, said device comprising an elongated bar or plate movable into and out of the path of said block and so positioned that its edge faces are intersected throughout their length by a plane parallel to said path, resilient means for actuating the bar toward the block and yieldingly maintaining the bar embedded therein, and cam mechanism successively operable to remove the bar to disengage the block and to release the bar for further actuation by said resilient means. 65

5. A device for forming a plurality of longitudinally aligned recesses in a moving block of plastic material, said device comprising a bar or plate 70

movable into and out of the path of said block and so positioned that its opposite edges are intersected substantially throughout their length by a plane parallel to said path, resilient means 5 for actuating the bar toward the block and yieldingly maintaining the bar embedded therein, and cam mechanism operable to move the bar after an interval of embedment to disengage the block and then to release the bar after an interval of 10 disengagement for further actuation by said resilient means.

6. A device for forming a plurality of longitudinally aligned recesses in a moving block of plastic material, said device comprising an elongated bar longitudinally movable into and out of the path of said block and so positioned that its opposite longitudinal edge faces are intersected throughout their length by a plane parallel to 15 said path, resilient means for actuating the bar toward the block and yieldingly maintaining the bar embedded therein, and cam mechanism successively operable to intermittently move the bar to disengage the block and then to release the bar for further actuation by said resilient means, 20 said bar providing corrugations extending in the general direction of movement of the block.

7. A device for forming a plurality of longitudinally aligned recesses in a moving block of plastic 25

material, said device comprising a member reciprocally movable transversely to the direction of movement of said block, an elongated bar or plate mounted on said member and movable thereby into and out of recess forming engagement with the block, spring means for moving said member to engage the bar with the block, and cam mechanism successively operable to move the member in the opposite direction to disengage the bar from the block and to release the member for 10 further actuation by said spring means.

8. A device for forming a plurality of longitudinally aligned recesses in a moving block of plastic material, said device comprising a member reciprocally movable transversely to the direction of 15 movement of said block, an elongated bar or plate mounted on said member and successively movable thereby into and out of recess forming engagement with the block, spring means for moving said member to embed the bar in the 20 block, and cam mechanism intermittently operable to actuate the member to remove the bar from the block after an interval of embedment therein, said mechanism being operable to release the member for movement by said spring 25 means to again embed the bar after an interval of removal from the block.

HENRY JANSEN.
